(57) **CLAIM**

The ornamental design for a portable electricity generator chassis, as shown and described.

DESCRIPTION

FIG. 1 is a frontal perspective view of a portable electricity generator chassis showing my new design, with the handles in a folded configuration;

FIG. 2 is an enlarged partial frontal perspective view of the handles of FIG. 1;

FIG. 3 is a frontal perspective view of the portable electricity generator chassis of FIG. 1, in which the handles are extended;

FIG. 4 is a front elevational view of the portable electricity generator chassis of FIG. 1;

FIG. 5 is a rear elevational view of the portable electricity generator chassis of FIG. 1;

FIG. 6 is a left side elevational view of the portable electricity generator chassis of FIG. 1;

FIG. 7 is a right side elevational view of the portable electricity generator chassis of FIG. 1;

FIG. 8 is a top plan view of the portable electricity generator chassis of FIG. 1; and,

FIG. 9 is a bottom plan view of the portable electricity generator chassis of FIG. 1.

The broken lines shown represent unclaimed subject matter and form no part of the claimed design.
